Assistant Examiner — Megan Rakos

(57) **CLAIM**

The ornamental design for a speaker as shown and described.

DESCRIPTION

The patent or application file contains at least one drawing executed in color. Copies of this patent or patent application publication with color drawing(s) will be provided by the Office upon request and payment of the necessary fee.

1. Speaker
2. Speaker
- 1.1: Perspective
- 1.2: Front
- 1.3: Back
- 1.4: Top
- 1.5: Bottom
- 1.6: Left
- 1.7: Right
- 2.1: Perspective
- 2.2: Front
- 2.3: Back
- 2.4: Top
- 2.5: Bottom
- 2.6: Left
- 2.7: Right

Reproductions 1.1 and 2.1 are perspective views; reproductions 1.2 and 2.2 are front views; reproductions 1.3 and 2.3 are back views; reproductions 1.4 and 2.4 are top views; reproductions 1.5 and 2.5 are bottom views; reproductions 1.6 and 2.6 are left views; reproductions 1.7 and 2.7 are right views.

The broken line areas with yellow highlighting shown in the drawings depict portions of the speaker that form no part of the claimed design.
